Filed July 16, 1961, Ser. No. 122,736

5 Claims. (Cl. 78—42)

The present invention relates generally to high energy rate forming machines; more particularly, the invention relates to dynamic forming machines adapted for repetitive cycling.

High energy rate forming machines for repetitive cycling operation have had a number of disadvantages and shortcomings. A considerable number of steps and control functions have generally been involved in such operation of the machine. Automatic cycling has generally required the use of relatively complex actuators. Some machines have required more than one hydraulic system for automatic repetitive cycling. Some have had the disadvantage and expense of losing or dumping quantities of operating gases on each cycle of operation. Such machines have had relatively extensive maintenance problems.

The present invention provides a high energy rate forming machine which is adapted for repetitive cycling of operation by a pressure-actuated floating reseating piston for reseating an actuator piston preparatory to operation. The machine is adapted for automatic repetitive cycling by a control system including electrically operating control valves which operate to apply reseating pressure to the reseating piston, to relieve the reseating pressure prior to operation, and to apply a triggering pressure to the actuator piston to initiate actuator operation. The machine preferably includes a frame on which an actuator is mounted and to which a bolster is connected. An actuator piston is cooperable with a wall in the actuator to provide a pressure seal between the piston and the wall separating areas of the piston. A ram connected with the actuator piston confronts the bolster. A floating reseating piston is slidable in the actuator on the side of the actuator piston opposite from the wall. Hydraulic reseating pressure is applied to the reseating piston to urge the piston toward the wall to establish the pressure seal and prior to actuator operation, this reseating pressure is relieved. Actuator operation is preferably initiated by the application of a triggering force to the actuator piston, preferably by a triggering pressure applied to an area of the actuator piston. The triggering force overbalances the forces on the piston to eliminate the pressure seal between the actuator piston and the wall, thereby releasing an actuating pressure upon an area of the actuator piston. The actuator piston is thereby impelled from the wall to impel the ram to impact the bolster.

In a preferred embodiment of the invention, an orifice is defined in the wall in the actuator and the above-mentioned pressure seal is established about this orifice. The wall separates an actuating pressure chamber and a set pressure chamber. A set pressure exerts a set force on the actuator piston to urge it toward the wall, and the actuating pressure acts oppositely on the actuator piston. The set pressure is introduced through an inlet tube which is secured to a bridge portion of the orifice wall which separates two portions of the orifice, and which extends into an axial bore in the actuator piston and in a thrust column which interconnects the piston and the ram. A frame structure includes guide rods which carry support pistons which are acted upon by pressure in damping assemblies to support the frame structure and the bolster. Upon impact of the ram on the bolster, the end portions of the guide rods are urged into damping cylinders in the damping assemblies to effect predeter-

mined deceleration of the frame and bolster assembly by forcing oil outwardly through graduated damping holes in the damping cylinder.

An electrically operated and automatically functioning pressure valve control system may preferably be utilized to provide automatic recycling or repetitive operation of the forming machine. A normally open electrically operated first valve permits oil under a reseating pressure to pass from a supply to the reseating piston. A switch is operable upon movement of the ram into its upward position, to close this valve to stop the supply of reseating pressure. An automatic switch is responsive to the pressure drop produced by the closing of the first valve and momentarily opens another valve to apply a burst of triggering pressure to an actuator piston area to effect overbalancing of the forces on the piston, thereby eliminating the pressure seal and releasing the actuating pressure upon an area of the actuator piston. This impels the actuator piston from the wall to impel the ram to impact the bolster.

It is therefore an object of the present invention to provide a high energy rate forming machine which is adapted for convenient and economical repetitive operation.

An object of the invention is the provision of a high energy rate forming machine which is adapted for automatic recycling with a relatively simple actuator.

It is an object of the invention to provide a high energy rate forming machine which provides automatic repetitive cycling with improved reliability, ease of control and efficiency.

An object of this invention is to provide a dynamic forming machine which provides convenient and efficient repetitive cycling with a relatively simple actuator by utilizing a floating reseating piston arrangement for reseating an actuator piston preparatory to repeat operation.

It is an object of the present invention to provide a high energy rate forming machine according to the foregoing object wherein a novel pressure inlet tube arrangement facilitates the use of the floating reseating piston by permitting overlapping travel of the reseating piston and the actuator piston.

An object of this invention is the provision of a high energy rate forming machine according to the foregoing objects wherein portions of an orifice wall are separated by a wall bridge portion which provides means for mounting the pressure inlet tube.

It is an object of the invention to provide a dynamic forming machine which provides improved efficiency and economy in repetitive operation by eliminating loss of operating gas on each cycle of operation.

An object of the present invention is to provide a high energy rate forming machine wherein an hydraulically actuated reseating piston reseats an actuator piston preparatory to repetitive actuator operation and wherein the reseating piston separates oil under a reseating pressure from operating gas pressure, thereby precluding loss of gas on each cycle of operation.

It is an object of the invention to provide a control valve system which facilitates automatic repetitive cycling of a dynamic forming machine utilizing a relatively simple high energy rate actuator.

Another object of the invention is the provision of a control valve system according to the foregoing object wherein automatic electrically operated valves apply reseating pressure to a reseating piston to reseat an actuator piston preparatory to operation, then relieve the reseating pressure from the reseating piston, and apply a triggering pressure to the actuator piston to overbalance the force thereon to initiate actuator operation.

Another object of the invention is to provide a high energy rate forming machine which substantially reduces the maintenance problems associated with automatic cycling high energy rate forming machines.

Other objects, features and advantages of the present invention will become apparent to those versed in the art from a consideration of the following description, the appended claims and the accompanying drawings, wherein:

FIGURE 1 is an elevational view, partially in section, of a preferred embodiment of the forming machine of the present invention;

FIGURE 2 is an enlarged sectional view taken at line 2-2 of FIGURE 1;

FIGURE 3 is a sectional view taken at line 3-3 of FIGURE 2;

FIGURE 4 is an enlarged fragmentary sectional view showing details of the actuator assembly utilized with the dynamic forming machine of FIGURE 1;

FIGURE 5 is an enlarged partial sectional view showing details of the damping assembly of the dynamic forming machine of FIGURE 1;

FIGURE 6 is an enlarged fragmentary sectional view showing details of a limit switch utilized with the dynamic forming machine of FIGURE 1;

FIGURE 7 is an enlarged sectional view, taken at line 7-7 of FIGURE 1; and

FIGURE 8 is a diagrammatic illustration of a triggering pressure system and a hydraulic reseating pressure system which may be utilized with the dynamic forming machine of FIGURE 1.

Referring to the drawings, and particularly to FIGURES 1 and 7, there is shown a preferred embodiment of the dynamic forging machine of the present invention. Two identical vertical support beams 10, each having a wide central web portion and end flanges 12, 14, are welded in spaced relation on opposite end portions of a base plate 16. The base plate is secured to a foundation 18 by bolts 20. A cover plate 22 is secured by screws to upper portions of the end flanges 14 of the beams 10, and another cover plate 24 is similarly secured by screws between the lower portions of flanges 14 of the beams.

A unitary frame and bolster assembly 26 includes an end plate 28 and a bolster assembly 30, which are rigidly interconnected by four guide rods 32. Threaded end portions of the guide rods extend through appropriate openings in the end plate, and each guide rod is secured to the end plate by nuts 34, 36 which engage a threaded upper portion of the guide rod and clamp end plate between them, as shown.

The bolster assembly 30 comprises an upper section 38 and a lower section 40. A threaded portion of each guide rod 32 extends through appropriate aligned openings in the bolster sections, and are secured to each guide rod by nuts 42, 44 which are disposed in recesses on opposite sides of the bolster assembly and which threadedly engage the guide rods. A die part 46 is secured to the bolster by bolts 48 which extend through openings in a flange portion of the die part. A die cavity or recess 50 is defined in the die part and a workpiece 52 is positioned atop the die.

As shown in FIGURES 1 and 5, an annular support piston 54 is secured to a threaded portion of the guide rod and spaced a short distance from its end. The piston is slidable in a cylindrical section 56 of a damping assembly 58. A peripheral bearing 60 is provided on the piston. The damping assembly includes an upper end cap 62, a lower end cap 64 and the cylindrical section 56, these parts being secured in clamped relation by a plurality of tie bolts 66 which extend through circularly arranged openings in the upper end cap and are secured by engagement of their threaded lower end portions in openings in the base plate 16. Pressure sealing for the damping assembly is provided by seal rings 68 positioned between the respective end caps and the cylindrical section 56 in appropriate grooves in the end caps.

4

A reduced end portion 70 of each guide rod is slideable within a damping cylinder 72, which is secured to the lower end cap 64 by engagement of its end portion in a threaded circular recess in the end cap. A plurality of damping orifices are provided in the damping cylinder. For a purpose which is hereinafter described in relation to the operation of the damping assembly, these orifices are graduated and decrease in size in accordance with their distance from the top of the damping cylinder, as shown. A pool or reservoir of oil is provided about the damping cylinder.

A support pressure chamber 74 in the damping assembly is defined by the cylindrical section 56, the lower end cap 64 and the support piston 54. The chamber is connected by a port 76 in the cylindrical section and a fluid coupling 78 with a source of support pressure (not shown). The support pressure acts on the support piston to support the machine assembly, including the frame and bolster assembly 26, the actuator assembly and the ram. The pressure provides the supporting force by acting upon the effective differential area between the two sides of the support piston, because the support pressure exists in the space above the piston.

An actuator assembly 80 is mounted on the frame and bolster assembly 26. The actuator assembly is secured to the end member 28 by tie rods 82 which extend through appropriate openings in the end plate and have their end portions in threaded engagement in a bottom end plate 84. The guide rods 32 extend through respective openings in the bottom plate 84, and two rod bearing halves are secured by screws in a circular recess in the plate about each of the guide rods. An actuator housing is formed by an upper end cap 86, a lower end member 88, cylindrical sections 90, 92, an orifice wall member 94 and the bottom plate 84, all of which are secured in clamped relation by the tie rods 82, as hereinbefore mentioned. Pressure sealing for the actuator housing is provided by resilient seal rings 96 between the cylindrical sections, the end caps and the orifice wall, the seal rings being disposed in appropriate grooves in the respective end caps and in the orifice plate, as shown.

Referring to FIGURES 1, 2 and 3, the orifice wall member 94 has an orifice defined therein, which is formed of a lower axial orifice portion 98 and two generally rectangular upper orifice portions 100, 102 separated by a bridge portion 104 of the orifice wall member. As shown, the bridge portion 104 is thinner than the remainder of the orifice wall, so that the upper orifice portions communicate with the lower orifice portion 98 through the space under the bridge portion 104. The orifice wall 94 separates an actuating pressure chamber 106 and a set pressure chamber 108 in the actuator housing.

An actuator piston 110 is slideable in cylindrical section 92 and in the set pressure chamber 108. A sealing ring in a peripheral groove of the piston provides pressure sealing between the piston and the cylindrical section 92. A thrust column 112 is secured by engagement of its threaded reduced end portion 114 (FIGURE 4) in an axial opening in the piston. The thrust column extends through the lower end of the actuator housing, and is slidably received in a bearing 116 mounted in the lower end member 88. A seal ring in a groove in the lower end member 88 about the thrust column provides pressure sealing.

An annular seal base 118 (FIGURE 4) is disposed in an end recess of the thrust column and confronts the orifice wall 94. The seal base is retained by a tube bearing 120 which is threadedly secured in an axial opening 122 in the thrust column. A seal ring 124 in an end of the thrust column provides pressure sealing between the seal base and the thrust column, and a seal ring 126 in a groove in the bearing provides pressure sealing between the seal base and the tube bearing. A circular resilient sealing element 128 is secured as by bonding in a circular

groove in the seal base in confronting relation with the surface of the orifice wall member 94.

A generally rectangular ram assembly 130 is attached to the thrust column by threaded engagement of an end portion of the thrust column in an opening in an upper ram section 132. Upper section 132 is secured to a main ram section 134 by bolts 136, as shown. The ram assembly 130 is slidably mounted on the four guide rods 32 by arcuate bearing elements 138 which are secured in arcuate recesses in the respective corners of the rectangular main ram section 134. Each arcuate bearing element is secured against a recess shoulder by a bolt 140. A male die part or punch 142 is secured by bolts to the lower surface of the ram.

A limit switch 144 is mounted in an opening in bottom end plate 34 and includes an insulating member 146 which threadedly engages an opening in the bottom end plate. A body member 148 is secured in a threaded bore in the insulating member. A helical spring 150 and a contact plunger 152 are mounted in an axial opening in the body member. The spring exerts a biasing force on an enlarged portion 154 of the plunger, and a cap member 156 retains the plunger. When the upper bolster section 132 contacts and depresses the plunger 152 of the switch, an electrical circuit is completed through the ram, the plunger 152, cap member 156 and a wire 158.

Referring to FIGURES 2, 3 and 4, a set pressure inlet tube 160 is secured to the bridge portion 104 of the orifice wall member by engagement of its threaded end portion in an opening in the bridge section and is securely locked by nuts 162, 164. A radial passage 166 in the orifice wall is connected with a source of set pressure (not shown) by a fluid coupling 168 and communicates with the set pressure inlet tube 160 through the opening in the orifice wall bridge section 104 in which the inlet tube 160 is threadedly secured. The set pressure inlet tube 160 extends into an axial bore 170 in the thrust column and is slidably received in the tube bearing 120. A sliding pressure seal between the tube bearing and the tube is provided by a seal ring in a groove in the tube bearing. A radial opening 172 in the thrust column communicates between the bore 170 and the set pressure chamber 108.

From the foregoing description and the drawings, it will be understood that the set pressure chamber 108 is connected with a source of set pressure (not shown) by the radial passage 172 and axial bore 170 in the thrust column, the set pressure inlet tube 160, the radial passage 166 in the orifice wall member, and the fluid coupling 168.

An actuating pressure chamber 106 is connected with a source of actuating pressure (not shown) by a passage 174 in the orifice wall member and a fluid coupling 176. A passage 178 in the orifice wall member and a fluid coupling 180 are connected with a source of triggering pressure (not shown) for a purpose hereinafter described.

An annular floating reseating piston 182 is slidable in the set pressure chamber 108 and is slideable on the thrust column by means of its axial bore 184. A recessed portion 186 of the piston serves a purpose which is herein-after described. Pressure sealing between the piston and cylindrical section 92 is provided by a seal ring in a peripheral groove of the piston, and sealing between the thrust column and the piston is provided by a seal ring in a groove in the bore of the piston.

The set pressure chamber 108 is connected with a source of hydraulic reseating pressure (shown in FIGURE 8) by a passage 188 in the lower end member 88 and by a fluid coupling 190. A pressure-responsive switch 192 communicates with the passage 188 and the fluid coupling through a passage 194, for a purpose herein-after described.

To prepare the machine for operation, quantities of gas under appropriate pressures are introduced into the

actuating pressure chamber 106, the set pressure chamber 108, and the support pressure chamber 74. The support pressure is introduced into chamber 74 (FIGURES 5 and 1) through the fluid couplings 78 and ports 76. This pressure is such that by acting on the support pistons 54 it exerts sufficient force to support the entire bolster and frame assembly 26 of the machine. A relatively high actuating pressure is introduced into actuating pressure chamber 106 through the fluid coupling 176 and the passage 174 in the orifice wall. A relatively low set pressure is established in set pressure chamber 108 from a source of set pressure (not shown) through fluid coupling 168, passage 166 in the orifice wall member, set pressure inlet tube 160, and the bore 170 and radial passage 172 in the thrust column. This pressure acts on the area of the actuator piston outside thrust column 112 to urge the actuator piston 110 toward the orifice wall member 94 to effect a positive pressure seal between the piston and the wall member by means of the circular resilient sealing element 128. The actuating pressure in chamber 106 is preferably sufficient in acting through orifice portions 100, 102 upon the actuator piston area within the circular sealing element 128, to substantially balance the opposing force of the set pressure on the piston.

To initiate operation of the machine, a triggering pressure is introduced through the fluid coupling 180 and the passage 178 in the orifice wall member 94 to act upon the area of actuator piston 110 radially outside the pressure seal between the annular resilient sealing element 128 and the orifice wall member. The force of the triggering pressure on this area effects sudden disengagement of the pressure seal at the resilient sealing element 128. The actuating pressure is thereby suddenly released upon the piston area radially outside the sealing element 128. The actuator piston is thereby suddenly impelled from the orifice wall, and the ram assembly 130 is impelled downwardly at high velocity.

In reaction to the rapid downward movement of the actuator piston and ram assembly, the entire frame and bolster assembly 26, including the guide rod 32 and the bolster assembly, moves upwardly a distance which is relatively shorter in proportion to the relative masses of the respective assemblies. The reduced end portions 70 of the guide rods being slideable in the damping cylinders 72, the upward movement of the guide rods causes their end portions 70 to draw oil into the damping cylinders through the damping openings 73 from the supply in the damping assembly.

The ram assembly impacts the bolster assembly at high velocity, the impact between the die part 142 on the ram and the die part 46 on the bolster assembly results in the high rate application of energy to effect forming of the workpiece by the die parts. The opposing movements of the ram assembly 130 and the frame and bolster assembly 26 increase the energy which is imparted to the workpiece 52.

After the impact of the ram upon the bolster, the frame and bolster assembly 26 moves downwardly. This downward movement urges the end portions 70 of the respective guide rods 32 into the damping cylinders to force the oil in the damping cylinders outwardly through the damping openings 73. Pressure differentials are thereby established across these openings which produce decelerating forces on the guide rods. Because of the graduated decreasing sizes of the damping orifices, the pressure differentials across the orifices increase and the decelerating forces increase as the guide rods move downwardly. The decelerating force therefore becomes progressively greater as the frame and bolster assembly moves downward, and predetermined or controlled deceleration of the frame and bolster assembly is thus effected.

After the downward movement of the frame and bolster assembly 26 has been stopped, the support pres-

sure in the chambers 74 of the damping assemblies urges the assembly upward and supports it in the position shown in FIGURE 1.

To prepare the actuator and the machine for repeat operation, the actuator piston must be reseated against the orifice wall member 94 to re-establish the pressure seal between them at the circular resilient sealing element 128, and to raise the ram assembly to its upward position. Reseating of the actuator piston 110 and the raising of the ram assembly 130 are effected by introducing a hydraulic reseating pressure into the set pressure chamber 108 beneath the floating reseating piston 182. This hydraulic reseating pressure urges the reseating piston upward to raise the actuator piston and the ram assembly. The floating reseating piston 182 may preferably contact the actuator piston, and the gas in the set pressure chamber is preferably compressed within the space defined between the pistons by the relief portion 186 of the reseating piston. The raising of the actuator piston by the action of the hydraulic reseating pressure on the reseating piston 182 effects compression of the actuating pressure into the actuating pressure chamber 106.

After the actuator piston is reseated the application of hydraulic reseating pressure to the reseating piston is stopped. This permits the pressure of the gas compressed in the set pressure chamber 108 to force the floating reseating piston 182 downward, thereby forcing the oil out of the set pressure chamber through the passage 188 and the fluid coupling 190, and seating the reseating piston against the lower end member 88 in the position shown in phantom outline in FIGURE 4. The expansion of the gas above the reseating piston re-establishes the original set pressure in set pressure chamber 108.

Upon the reseating of the actuator piston 110, the trapping of pressure in the space defined between the orifice wall member 94 and the actuator piston 110 by the circular resilient sealing element 128 and the seal ring between cylindrical section 92 and the piston, is prevented by relieving pressure from this space through the passage 178 in the orifice wall and the fluid coupling 180. If it were not released, pressure trapped in this space would act upon the actuator piston area radially outside the sealing element 128 and would oppose the force exerted oppositely upon the piston by the set pressure. Proper re-establishment of the pressure seal at the resilient sealing element 128 could not be effected, because the actuating pressure in chamber 106 would be more than sufficient to overbalance the force exerted oppositely on the actuator piston by the set pressure. This would preclude actuator operation, because the piston would be moved and the seal would be disengaged by the action of a relatively low pressure in the actuating pressure chamber 106, instead of by the proper actuating pressure.

The floating reseating piston 182 serves the important function of separating an oil system and a gas system. It is highly desirable to utilize an hydraulic system and hydraulic reseating pressure, because of its positive action, rapidity and efficiency. The separation of the oil and gas systems by the floating piston prevents mixing of gas and oil, which would involve problems. Absorption of gas in the set pressure chamber into the oil would produce a drop in set pressure. It would also result in substantial losses of gas by the venting thereof from the hydraulic system. Further, absorption of gas into the oil would produce a compressible foamy mixture. This would result in relatively inefficient operation and would require extra time for reseating. The pump supplying hydraulic pressure could not function properly and the compressible mixture and pump life would be much shorter.

The utility of the set pressure inlet tube arrangement is apparent from the foregoing description. It permits

overlapping travel of the actuator piston 110 and the floating reseating piston 182. An inlet port for supplying set pressure cannot effectively be provided in the wall of the actuator, because of the overlapping travel. It would be difficult to insure proper positioning or alignment of the pistons and an inlet port at the times when set pressure must be admitted. The sealing rings in the peripheral grooves in the actuator piston and the reseating piston would have relatively short service lives if such an inlet port were used, because they would tend to be damaged in moving past the inlet port.

FIGURE 8 schematically illustrates an automatic hydraulic reseating pressure system and an automatic gas triggering pressure system which may preferably be utilized for the automatic repetitive recycling of the dynamic forging machine of the invention.

A normally closed solenoid-operated valve 196 is connected in the fluid coupling 180 which interconnects the passage 178 in the orifice wall member 94 with a source of triggering pressure (not shown). Actuation of the valve admits triggering pressure through the coupling 180 to the passage 178. A normally open solenoid-operated valve 198 communicates with the line 180 and normally provides communication between the passage 178 in the orifice wall and the exterior atmosphere. Upon actuation the valve closes to prevent release of pressure from the passage 178 to the atmosphere. As indicated schematically in FIGURE 8, valves 196 and 198 are electrically connected with the pressure-operated switch 192 through relays 200, 202, respectively.

As hereinbefore described relative to FIGURE 4, the fluid coupling 190 interconnects passage 188 below floating piston 182 with a source of hydraulic reseating pressure, and the pressure-responsive switch 192 communicates with line 190 and passage 188. A hydraulic pump 204 powered by a motor 206 is mounted in the line 190 and supplies oil under a reseating pressure from reservoir 208 through the coupling 190 and the passage 188 to the set pressure chamber beneath the floating piston 182. A normally open solenoid-actuated valve 210 is connected in the line 190, and actuation of the valve stops the application of oil under the reseating pressure through the line. A relief valve 212 is connected with coupling 190 by a by-pass coupling 214 and permits oil under pressure from the pump 204 to pass directly back to the reservoir when the valve 210 is closed. A normally closed solenoid-operated valve 216 communicates through a coupling 218 with coupling 190 and passage 188. Actuation thereof releases hydraulic pressure from the set pressure chamber beneath the floating piston 182 and permits the oil to pass to the reservoir 208.

The automatic electrically operated hydraulic reseating pressure system and triggering pressure system of FIGURE 8 effect automatic repetitive cycling of the dynamic forming machine of FIGURES 1 through 7.

Referring to FIGURE 8, at the start of a cycle of operation of the machine, a relay system (not shown) closes the valve 216 and opens the valve 210, while valve 198 is open to atmosphere and valve 196 is closed. The open valve 210 admits oil from the pump 212 to the reseating piston, and the closed valve 216 prevents the loss of reseating pressure from the set pressure chamber 108 to the reservoir 208. Oil under the reseating pressure passes through the coupling 190 and passage 188 to the floating reseating piston. The reseating piston is thereby urged toward or against actuator piston 110 and the actuator piston is moved to its upward position shown in FIGURE 4, wherein a positive pressure seal is provided between the orifice wall 94 and the actuator piston by the annular sealing element 128. The gas in set pressure chamber 108 between the pistons is substantially compressed within the space defined by the relief portion 186 of the reseating piston.

The upward movement of the actuator piston to the position shown in FIGURE 4 carries the ram assembly 130 to its upward position, as shown in FIGURE 1. As the ram assembly moves into this position its upper section 132 contacts and depresses the plunger 152 of limit switch 144. The switch initiates operation of a relay system (not shown) which after a time delay closes the solenoid operated valve 210, opens the solenoid operated valve 198, and opens the valve 216 (FIGURE 8). The closing of valve 210 stops the application of oil under reseating pressure from the pump to the reseating piston. The opening of valve 198 releases to the exterior atmosphere pressure which may be trapped between the actuator piston and the orifice wall in the space defined between resilient sealing element 128 and the peripheral sealing ring 15 on the actuator piston, for the purpose which is hereinbefore described. The opening of valve 216 permits oil under the reseating pressure to pass from the set pressure chamber to the reservoir. The gas compressed in set pressure chamber 108 above the reseating piston 182 urges the reseating piston downwardly to the position shown in phantom outline in FIGURE 4. It is seated against lower end member 88 of the actuator assembly. This downward movement of the reseating piston forces the oil through passage 188 and coupling 190 to the reservoir 208.

Upon the seating of the reseating piston in the position shown in phantom outline in FIGURE 4, the pressure in the passage 188 and coupling 190 drops substantially to zero. The pressure-responsive switch 192 responds to this pressure drop and acts through the relay system 202, 200, respectively to close the valve 198 and to momentarily open the valve 196. The closing of valve 198 prevents loss of triggering pressure to the exterior atmosphere. The momentary opening of valve 196 admits a burst of triggering pressure from the source of triggering pressure (not shown) through the coupling 180 into the space defined radially outside the circular resilient sealing element 128 and within the peripheral sealing ring of the actuator piston. This burst of triggering pressure to this piston area unseats the actuator piston from the orifice wall member 94 and disengages the pressure seal. The actuating pressure in chamber 106 is thereby suddenly applied to the actuator piston area readily outside the resilient sealing element 128, and the actuator piston is rapidly impelled downwardly.

The downward movement of the ram and the impacting of the workpiece carried by the bolster is followed by the operation of the damping assembly, as hereinbefore described. A cycle of operation of the machine is thus completed, and a new cycle commences with the opening of valve 210 and the closing of valve 216 by the operation of the relay system.

From the foregoing description and from the drawings, it will be understood that the triggering pressure system and the hydraulic reseating pressure system, shown diagrammatically in FIGURE 8, effect automatic repetitive operation of the dynamic forming machine of the invention.

From the foregoing description, those versed in the art will appreciate that the present invention achieves the objects and realizes the advantages hereinbefore mentioned.

Although specific embodiments of the present invention have been illustrated and described herein, it will be understood that the same are merely exemplary of presently preferred embodiments capable of attaining the objects and advantages hereinbefore mentioned, and that the invention is not limited thereto; variations will be readily apparent to those versed in the art, and the invention is to be given its broadest possible interpretation within the terms of the appended claims.

I claim:

1. A high energy rate forming machine comprising

frame means, actuator means carried by the frame means, bolster means connected with the frame means, an actuator piston slidable in the actuator and confronting a wall therein, resilient sealing means between said piston and the wall for providing a pressure seal therebetween defining separate areas of the actuator piston, ram means connected with said actuator piston and confronting said bolster means, means establishing an actuating pressure in the actuator, a floating reseating piston slidable in the actuator on the opposite side of said actuator piston from said wall, an oil reservoir, conduit means communicating between the reservoir and the reseating piston, pump means for supplying oil under a reseating pressure from said reservoir through the conduit means to the reseating piston, electrically operable normally open first valve means in the conduit means between the reservoir and the reseating piston, electrically operable normally closed second valve means interconnecting said conduit means and the reservoir, electrical means for opening said first valve means to admit oil under the reseating pressure from the pump means to the reseating piston and to close said second valve means to prevent loss of reseating pressure to the reservoir, said reseating pressure urging the reseating piston and the actuator piston toward said wall to prepare the actuator for operation and to move the ram means to its upward position, electrically operable normally open third valve means interconnecting said second actuator piston area and the exterior atmosphere, limit switch means operable upon movement of the ram means into said upward position to close the first valve means to stop the supply of oil under reseating pressure from the pump means and to open the third valve means to relieve pressure trapped between the actuator piston and said wall, and to open the second valve means to release oil under reseating pressure from the reseating piston to the reservoir, electrically operable normally closed fourth valve means interconnecting a source of triggering pressure with said second actuator piston area, and switch means responsive to the pressure drop caused by said closing of the first valve means to close the third valve means to prevent loss of triggering pressure to the exterior atmosphere and to momentarily open the fourth valve means for a momentary application of triggering pressure to said second actuator piston area to overbalance the forces on the piston to eliminate said pressure seal and release the actuating pressure upon said second actuator piston area, whereby the actuator piston is impelled from said wall to impel said ram means to impact the bolster means.

2. A high energy rate forming machine comprising frame means, actuator means carried by the frame means, bolster means connected with the frame means, a wall defining two orifice portions separated by a wall bridge portion, said orifice wall separating an actuating pressure chamber and a set pressure chamber in said actuator, an actuator piston slidable in said set pressure chamber and confronting said orifice wall, a thrust column connected with the actuator piston and extending from the actuator, said actuator piston and said orifice wall being adapted for cooperation to provide a pressure seal therebetween about said orifice, a set pressure inlet tube secured to said wall bridge portion and extending into an axial bore in the actuator piston and in the thrust column, said thrust column and actuator piston being movable relative to the inlet tube, said thrust column having passage means communicating between the thrust column bore and the set pressure chamber, means for introducing a set pressure through said inlet tube, said bore and said passage into the set pressure chamber, said set pressure acting on the actuator piston to urge the piston toward the wall, means for establishing a relatively high actuating pressure in the actuating pressure chamber to act on the actuator piston in a direction opposite to the action of the set pressure, ram means connected with the thrust column and confronting said bolster means, a floating reseating piston slidable

in the actuator on the opposite side of the actuator piston from said wall, means for applying hydraulic reseating pressure to said reseating piston to urge the actuator piston toward the wall against the action of the actuating pressure to establish said pressure seal about the orifice to prepare the actuator for operation, means for relieving the reseating pressure from the reseating piston preparatory to actuator operation, said set pressure in the set pressure chamber exerting a set force urging the actuator piston toward the orifice wall to maintain said pressure seal, and means for applying a triggering force to the actuator piston to cooperate with the actuating pressure in overbalancing the set force to eliminate said pressure seal and release the actuating pressure upon an increased area of the actuator piston, whereby the actuator piston is impelled from said wall to impel the ram means to impact the bolster means.

3. A high energy rate forming machine comprising frame means, actuator means carried by the frame means, bolster means connected with the frame means, a wall defining an orifice between an actuating pressure chamber and a set pressure chamber in said actuator, an actuator piston slideable in said set pressure chamber and confronting said orifice wall, resilient sealing means positioned between the actuator piston and said orifice wall for providing a pressure seal therebetween about the orifice and separating first and second area of the actuator piston, means for establishing a relatively low set pressure in the set pressure chamber to act on the actuator piston to urge the piston toward the wall, means for establishing a relatively high actuating pressure in the actuating pressure chamber to act on the actuator piston in a direction opposite to the action of the set pressure, ram means connected with the actuator piston and confronting said bolster means, a floating reseating piston slideable in the actuator on the opposite side of the actuator piston from said wall, an oil reservoir, conduit means communicating between the reservoir and the reseating piston, pump means for supplying oil under a reseating pressure from said reservoir through the conduit means to the reseating piston, electrically operable normally open first valve means in the conduit means between the reservoir and the reseating piston, electrically operable normally closed second valve means interconnecting said conduit means and the reservoir, electrical means for opening said first valve means to admit oil under the reseating pressure from the pump means to the reseating piston and to close said second valve means to prevent loss of reseating pressure to the reservoir, said reseating pressure urging the reseating piston and the actuator piston toward said wall to prepare the actuator for operation and to move the ram means to its upward position, electrically operable normally open third valve means interconnecting said second actuator piston area and the exterior atmosphere, limit switch means operable upon movement of the ram means into said upward position to close the first valve means to stop the supply of oil under reseating pressure from the pump means and to open the third valve means to relieve pressure trapped between the actuator piston and said wall, and to open the second valve means to release oil under reseating pressure from the reseating piston to the reservoir, electrically operable normally closed fourth valve means interconnecting a source of triggering pressure with said second actuator piston area, and switch means responsive to the pressure drop caused by said closing of the first valve means to close the third valve means to prevent loss of triggering pressure to the exterior atmosphere and to momentarily open the fourth valve means for a momentary application of triggering pressure to cooperate with the force of the actuating pressure on said first actuator piston area to overbalance the forces on the piston to eliminate said pressure seal and release the actuating pressure upon said second actuator piston area, whereby the actuator piston is impelled from

said wall to impel said ram means to impact the bolster means.

4. A high energy rate forming machine comprising frame means, actuator means carried by the frame means, bolster means connected with the frame means, a wall defining two orifice portions separated by a wall bridge portion, said orifice wall separating an actuating pressure chamber and a set pressure chamber in said actuator, an actuator piston slideable in said set pressure chamber and confronting said orifice wall, a thrust column connected with the actuator piston and extending from the actuator, said actuator piston and said orifice wall being adapted for cooperation to provide a pressure seal therebetween about said orifice, a set pressure inlet tube secured to said wall bridge portion and extending into an axial bore in the actuator piston and in the thrust column, said thrust column and actuator piston being movable relative to the inlet tube, said thrust column having passage means communicating between the thrust column bore and the set pressure chamber, means for introducing a set pressure through said inlet tube, said bore and said passage into the set pressure chamber, said set pressure acting on the actuator piston to urge the piston toward the wall, means for establishing a relatively high actuating pressure in the actuating pressure chamber to act on the actuator piston in a direction opposite to the action of the set pressure, ram means connected with the thrust column and confronting said bolster means, a floating reseating piston slideable in the actuator on the opposite side of the actuator piston from said wall, an oil reservoir, conduit means communicating between the reservoir and the reseating piston, pump means for supplying oil under a reseating pressure from said reservoir through the conduit means to the reseating piston, electrically operable normally open first valve means in the conduit means between the reservoir and the reseating piston, electrically operable normally closed second valve means interconnecting said conduit means and the reservoir, electrical means for opening said first valve means to admit oil under the reseating pressure from the pump means to the reseating piston and to close said second valve means to prevent loss of reseating pressure to the reservoir, said reseating pressure urging the reseating piston and the actuator piston toward said wall to prepare the actuator for operation and to move the ram means to its upward position, limit switch means operable upon movement of the ram means into said upward position to close the first valve means to stop the supply of oil under reseating pressure from the pump means and to open the second valve means to release oil under reseating pressure from the reseating piston to the reservoir, said set pressure in the set pressure chamber exerting a set force urging the actuator piston toward the orifice wall to maintain said pressure seal, and means for applying a triggering force to the actuator piston to cooperate with the actuating pressure in overbalancing the set force to eliminate said pressure seal and release the actuating pressure upon an increased area of the actuator piston, whereby the actuator piston is impelled from said wall to impel the ram means to impact the bolster means.

5. A high energy rate forming machine comprising frame means, actuator means carried by the frame means, bolster means connected with the frame means, a wall defining two orifice portions separated by a wall bridge portion, said orifice wall separating an actuating pressure chamber and a set pressure chamber in said actuator, an actuator piston slideable in said set pressure chamber and confronting said orifice wall, a thrust column connected with the actuator piston and extending from the actuator, resilient sealing means positioned between the actuator piston and said orifice wall for providing a pressure seal therebetween about the orifice and defining first and second areas of the actuator piston, a set pressure inlet tube secured to said wall bridge portion and extending into an axial bore in the actuator piston and in the thrust column, said thrust column and actuator piston being movable

relative to the inlet tube, said thrust column having passage means communicating between the thrust column bore and the set pressure chamber, means for introducing a set pressure through said inlet tube, said bore and said passage into the set pressure chamber, said set pressure acting on the actuator piston to urge the piston toward the wall, means for establishing a relatively high actuating pressure in the actuating pressure chamber to act on the actuator piston in a direction opposite to the action of the set pressure, ram means connected with the thrust column and confronting said bolster means, a floating reseating piston slideable in the actuator on the opposite side of the actuator piston from said wall, an oil reservoir, conduit means communicating between the reservoir and the reseating piston, pump means for supplying oil under a reseating pressure from said reservoir through the conduit means to the reseating piston, electrically operable normally open first valve means in the conduit means between the reservoir and the reseating piston, electrically operable normally closed second valve means interconnecting said conduit means and the reservoir, electrical means for opening said first valve means to admit oil under the reseating pressure from the pump means to the reseating piston and to close said second valve means to prevent loss of reseating pressure to the reservoir, said reseating pressure urging the reseating piston and the actuator piston toward said wall to prepare the actuator for operation and to move the ram means to its upward position, electrically operable normally open third valve means interconnecting said second actuator piston area and the exterior atmosphere, limit switch means operable

5 upon movement of the ram means into said upward position to close the first valve means to stop the supply of oil under reseating pressure from the pump means and to open the third valve means to relieve pressure trapped between the actuator piston and said wall, and to open the second valve means to release oil under reseating pressure from the reseating piston to the reservoir, electrically operable normally closed fourth valve means interconnecting a source of triggering pressure with said second actuator piston area, and switch means responsive to the pressure drop caused by said closing of the first valve means to close the third valve means to prevent loss of triggering pressure to the exterior atmosphere and to momentarily open the fourth valve means for a momentary application of triggering pressure to cooperate with the force of the actuating pressure on said first actuator piston area to overbalance the forces on the piston to eliminate said pressure seal and release the actuating pressure upon said second actuator piston area, whereby the actuator piston is impelled from said wall to impel said ram means to impact the bolster means.
